(57) **CLAIM**

The ornamental design for a massage gun with multiple heads, as shown and described.

DESCRIPTION

FIG. 1 is a first perspective view of a massage gun with multiple heads showing my new design;
FIG. 2 is a second perspective view thereof;
FIG. 3 is a front elevation view thereof;
FIG. 4 is a rear elevation view thereof;
FIG. 5 is a left side elevation view thereof;
FIG. 6 is a right side elevation view thereof;
FIG. 7 is a top plan view thereof;
FIG. 8 is a bottom plan view thereof; and,
FIG. 9 is an enlarged view of the selected portion 9 in FIG. 3.

The dash-dash broken lines shown in the drawings depict portions of the massage gun with multiple heads that form no part of the claimed design. The dot-dash broken lines in FIGS. 3 and 9 illustrate the periphery of the enlarged views of the massage gun with multiple heads and form no part of the claimed design.
